UNITED STATES PATENT OFFICE.

VICTOR GERO, OF PHILADELPHIA, PENNSYLVANIA.

SPOOL HEAD.

Application filed March 21, 1922. Serial No. 545,435.

To all whom it may concern:

Be it known that I, VICTOR GERO, a citizen of the United States, and a resident of Philadelphia, county of Philadelphia, State 5 of Pennsylvania, have invented certain new and useful Improvements in Spool Heads, of which the following is a specification.

Some of the objects of the present invention are to provide an improved head construction for spools or bobbins; to provide 10 means for overcoming the delays and expense incident to the breaking or displacement of the heads of spools or bobbins such for example as employed in Axminster 15 looms; to provide a spool head construction wherein the head is rigidly secured against relative turning and axial movement on the body of the spool; to provide a spool head having a tension spring bearing surface 20 which is capable of withstanding the knocks and general abuse to which such a spool is subject; to provide a complete unitary head and cap arranged to be rigidly fixed to the 25 end of a spool body; and to provide other improvements as will hereinafter appear.

In the accompanying drawings, Fig. 1 represents a side elevation, in part section, of a spool embodying one form of the present invention; Fig. 2 represents a perspective of the parts forming the end and head 30 of the spool; and Fig. 3 represents an axial section of one end of the spool.

Referring to the drawings, one form of the present invention is here shown as applied to a spool body 10, of the type employed 35 for weaving tufted fabrics such as Axminster rugs or the like, and having an axially disposed groove 11 extending throughout the length of the body 10 for retaining the 40 tufts in the ordinary manner. It will be understood, however, that the invention is not limited in use to the particular spool body here shown, as this is only by way of example.

45 For the purpose of providing means to accurately locate the tuft frame (not shown) with respect to the spool body 10 and also to prevent end displacement of the tufts or other material carried by the body 10, two 50 heads 12 and 13 are provided, one for each end of the body 10. Each of these heads 12 and 13 is of greater diameter than the diameter of the body 10, and has a face recess 14 of the same contour as the end of the body 55 10 and of a size to snugly receive the respective body ends. These heads 12 and 13

are preferably of wood, though any material suitable for the purpose can be employed, and provide respectively peripheral, circular faces 15 and 16 for a purpose as will 60 hereinafter appear. A through opening 17 is formed in each of the heads for the passage of the tuft retaining means, and in assembled condition these openings 17 are in alignment with the body groove 11, as will 65 be understood.

In order to secure the heads 12 and 13 rigidly to the body 10, each head is formed integral with a stem or plug, the stem 20 of the head 12 being arranged to seat snugly 70 with an axially disposed hole 21 in the end of the body 10, while the stem 22 of the head 13 is arranged to similarly fit within a like hole 23 in the other end of the body. In assembled condition the two stems 20 and 75 22 are firmly held respectively by dowel pins 24 passing transversely through the body 10 and the respective stems 20 and 22. This forms a positive interlocking connection to prevent relative turning of the heads 80 with respect to the body 10, as well as preventing axial movement.

As a means to maintain a uniformly smooth circumferential surface for the tension springs of the usual tuft frames to ride 85 upon head caps 25 and 26 are provided, one for each head 12 and 13, each cap being arranged to fit over its head with the flanged annular side portion or rim 27 thereof in frictional engagement with the head face 90 15 or 16, as the case may be. In practice these caps 25 and 26 are preferably made of metal and are forced on the heads 12 and 13 by pressure and thus have such a tight fit that relative movement is impossible. If 95 desired, however, and as an additional safeguard, fastening means, such as screws 28, may be also employed to maintain the proper relative position of the caps 25 and 26 upon the respective heads 12 and 13. 100 These caps 25 and 26 are both provided with apertures 30 which are arranged in assembled condition to register with the openings 17 to permit access to the groove 11 from the spool ends as will be understood. 105

In order to provide means for properly supporting the ends of the spool, it is preferable to employ a stud 31 which passes axially through the head 12 and is driven 110 into one end of the body 10 until a flange 32 of the stud 31 abuts the outer face of the

head 12 and leaves the pin portion 33 projecting axially through the cap 25. The opposite end of the body 10 is provided with an axially located socket 34 to receive a similar stud 35 and its flange 36, the socket 34 having a depth sufficient to permit the stud 35 to be moved inwardly far enough to bring its normally projecting pin 37 within the plane of the outer face of the cap 26. A spring 38 encircles the stud 35 and seats between the end of the socket 34 and the flange 36, and is normally under compression to maintain and return the pin 37 to its projecting position. It will be understood that the flange 36 in normal position abuts the inner face of the cap 26 while the pin 37 projects an operative distance through the cap.

In assembling the complete spool, the heads 12 and 13 are respectively fitted to the spool ends by inserting the stems 20 and 22 in the respective holes 21 and 23, and then fastening them by driving in the dowels 24. The caps 25 and 26 not only form a protection for the heads but become a part thereof which provides a solid rim of uniform diameter upon which the tension spring parts ride and one which is capable of resisting such blows as would dent or otherwise damage a head of ordinary construction. Furthermore, the rigid relation between the foresaid caps and their heads make it impossible for the adjustment of the tuft frame to change, a feature which is of considerable importance. The cap over the head, also, forms a means to prevent wear on that part of the head which is in contact with the pin, such wear being a source of constant trouble in spool heads as at present constructed because it causes the spool end to have an eccentric motion which causes an uneven pile and low rows in the fabric. By the present invention the portion of the metal cap encircling the pin entirely eliminates wear upon the head. While the preferred form of the invention embodies a cap arranged to fit over the spool head, it is to be understood the invention is not so specifically limited as any form of rim and pin protecting means for a head is within the scope of the invention in its broad aspect.

Furthermore the stem or plug is positively secured to the spool body so that differences in the wood, changes in atmospheric conditions, and the torque of the heads cannot cause loosening of the plug or allow it to pull out when in use.

While only a single form is shown in which this invention may be embodied, it is to be understood that the invention is not limited to any specific construction, but might be applied in various forms without departing from the spirit of the invention or the scope of the appended claims.

Having thus described my invention, I claim:

1. In a spool or bobbin, the combination of a spool body, a head arranged to be rigidly secured to said body, a protecting rim circumferentially arranged about said head, and a pin projecting axially through said head.

2. In a spool or bobbin, the combination of a spool body, a head having a stem interfitting with said body, means for fastening said stem to said body, a pin projecting axially from said head, and a cap fitting over said head and pin and rigidly secured to said head.

3. In a spool or bobbin, the combination of a spool body, a head having a stem interfitting with said body, means for fastening said stem to said body, a spring pressed pin projecting axially from said head, and a cap fitting over said head and pin and rigidly secured to said head.

4. In a spool or bobbin, the combination of a spool body having a groove extending throughout the length thereof and an axially located socket, a head having a through opening located in alinement with said groove, an axially disposed stem integral with said head and arranged to fit tightly in said socket, means for rigidly securing said stem and body together to prevent relative movement, and a pin mounted to project axially from said head.

Signed at Philadelphia, in the county of Philadelphia, and State of Pennsylvania, this 15th day of March, 1922.

VICTOR GERO.
